UNITED STATES PATENT OFFICE

167,660

CHRISTMAS ORNAMENT

Milton M. Schrager, Far Rockaway, N. Y.

Application September 27, 1951, Serial No. 16,762

Term of patent 7 years

(Cl. D29—1)

To all whom it may concern:

Be it known that I, Milton M. Schrager, a citizen of the United States of America, residing in Far Rockaway, county of Queens, and State of New York, have invented a new, original, and ornamental Design for a Christmas Ornament, of which the following is a specification, reference being had to the accompanying drawing, forming part thereof,

Fig. 1 is a top plan view of a Christmas ornament showing my new design.

Fig. 2 is an edge view thereof.

I claim:

The ornamental design for a Christmas ornament, substantially as shown.

MILTON M. SCHRAGER.
